UNITED STATES PATENT OFFICE.

THOMAS BURKE, OF NEW YORK, N. Y.

IMPROVEMENT IN BUNGS.

Specification forming part of Letters Patent No. 128,014, dated June 18, 1872.

Specification describing a new and useful Improvement in Barrel-Bungs, invented by THOMAS BURKE, of the city, county, and State of New York.

This invention relates to a new and useful improvement in the bungs of barrels, hogsheads, and all similar vessels; and consists in the construction and arrangement of parts hereinafter described.

In the accompanying drawing, Figure 1 is a top view, with a portion broken away to show the groove of the fastening-bar. Fig. 2 is a vertical cross-section of Fig. 1 taken on the line *x x*.

Similar letters of reference indicate corresponding parts.

A represents a tubular shell, which is screwed into the barrel or vessel, where it may be secured by wood-screws through the flange *B*, as represented. *B'* represents the barrel. This shell is to be fastened into the barrel water-tight, and may be packed with canvas or elastic packing *C*, as seen in the drawing. Projecting inward from the bottom of the shell is the valve-seat *D*, and near the top are two inclined grooves, *E E*, placed opposite each other, and running from the opening *F F* downward a little less than half way round the inside of the shell. *G* is the valve or stopper, which is dropped into the shell and rests upon the valve-seat *D*. The valve *G* is composed of either part metal and part

cork, wood, or other packing, or altogether of wood and with or without packing. In this example of my invention, *H* is metal and *I* is cork. The valve is made tight and pressed down upon the seat *D* by the bar *J*, which spans the shell and enters the grooves *E E*, as represented in Fig. 1. This bar is confined to the valve by the central pin or lug *K*, and turns thereon. It enters the grooves *E E* through the opening *F F*, and when turned the inclined grooves carry it downward, which tightens the valve. This bar *J* may be cast or fixed rigidly to the valve or projecting lips, or lugs may be cast on the valve which will enter the grooves.

I do not confine myself to the precise form of the parts described, as variations may be made without departing from my invention.

Having thus described my invention, I claim as new and desire to secure by Letters Patent—

A bung consisting of the tube *A*, flanged at *B*, slotted at *F F*, oppositely grooved at *C E*, and having the valve-seat *D*, the valve *G*, formed of metal *H* and cork *I*, and the bar *J*, all relatively constructed and arranged as and for the purpose set forth.

THOMAS BURKE.
